UNITED STATES PATENT OFFICE.

LEWIS S. LEE, OF PHILADELPHIA, PENNSYLVANIA.

DESIGN FOR A CARRIAGE-ROBE.

SPECIFICATION forming part of Design No. 20,243, dated October 28, 1890.

Application filed October 31, 1889. Serial No. 328,847. Term of patent 14 years.

To all whom it may concern:

Be it known that I, LEWIS S. LEE, a citizen of the United States, residing at Philadelphia, in the county of Philadelphia and State of Pennsylvania, have invented and produced a new and original Design for Carriage-Robes, of which the following is a specification.

The design is shown in the drawings which accompany this specification, forming a part thereof.

Figure 1 is a plan view of a carriage-robe embodying my design; and Fig. 2 is an illustrative view of the same, showing the arrangement and location of the design upon the body of the robe.

The leading feature of the design consists of transverse pattern-bars upon the body of the robe at a distance from the ends.

A is the body of the robe. Extending across the body A and at considerable distance from

the ends are the patterns B, constituting transverse bars. The location of the transverse pattern-bars B at considerable distance from the ends of the robe exposes them to view on the sides of the legs of the person or persons in the vehicle when the robe is in use, as is shown in Fig. 2. Each of the transverse pattern-bars B consists of two straight transverse bars, with an intermediate ornamental pattern b arranged between.

What I claim is—

The design for a carriage-robe, substantially as described, and shown in the accompanying drawings.

In testimony of which invention I have hereunto set my hand.

LEWIS S. LEE.
